HAND MICROPHONE FOR A DICTATING MACHINE

Garabed Barsumian, Monroe, Conn., assignor to Dictaphone Corporation, Bridgeport, Conn., a corporation of New York

Application March 25, 1959, Serial No. 55,154

Term of patent 14 years

(Cl. D26—14)

I claim:

The ornamental design for a hand microphone for a dictating machine, substantially as shown.
